UNITED STATES PATENT OFFICE

FREDERICK H. PERRY, OF BEVERLY, MASSACHUSETTS, ASSIGNOR TO UNITED SHOE MACHINERY CORPORATION, OF PATERSON, NEW JERSEY, A CORPORATION OF NEW JERSEY

MACHINE FOR OPERATING UPON INSOLES

Application filed February 9, 1921. Serial No. 448,572.

The present invention relates to machines for operating upon insoles for boots and shoes, and more particularly to a machine for trimming the margins of manufactured insoles such as are used in making standardized welt shoes.

In making such standardized shoes, automatic machinery is employed in which the operating instrumentalities and the shoe are moved relatively through a predetermined path by mechanical means to transfer the point of operation around the shoe. To obtain satisfactory results by the use of such machinery, it is necessary that all insoles of the same size and style be alike in all dimensions, particularly with regard to the relation of the sewing-rib to the edge of the insole. An example of a manufactured insole, adapted for use in a welt shoe of the type above referred to, is disclosed in United States Letters Patent No. 1,578,359, granted March 30, 1926, on my application. The insole described in said Letters Patent is of laminated construction, being built up of one or more body layers of sheet insole material and an outside layer, preferably of textile material, this layer having a grooved sewing-rib moulded therein. In order to provide material to form the sewing-rib, the layer of textile material is died out to a larger size than the body layers, it being intended to make such allowance for the sewing-rib, that when the rib has been moulded, the layer of textile material will be exactly the same size as the body layers. It has been found difficult or impracticable uniformly to obtain this result and consequently the relation of the sewing-rib to the edge of the insole is liable to vary in the completed insoles. To avoid this difficulty, it is now proposed to die out all of the component layers of the insole preliminarily to such a size that, when assembled, the size of the insole will be slightly greater than that ultimately desired and subsequently to trim the insole to the requisite size having due regard to the desired location of the sewing-rib relative to its edge.

One of the objects of the present invention is to provide an efficient and reliable machine

for trimming the margins of welt insoles so as to produce an insole the sewing-rib of which will bear a predetermined relation to the edge of the trimmed insole.

With this object in view, one feature of the invention comprises the provision, in a machine for operating upon welt insoles, of a knife for trimming the margin of the insole, and a pattern adapted to guide the knife and locate the insole thereon by an engagement with its sewing-rib so that the margin of the insole will project beyond the edge of the pattern to be traversed by the knife. In the illustrated embodiment of this feature of the invention, the pattern comprises a flat plate, the edge of which serves to guide the trimming knife, while its upper face is recessed to receive the sewing-rib of the insole as the latter is placed, ribbed face down, upon the pattern by the operator. The pattern is constructed and arranged to support the insole by engagement with its margin and to locate the insole relative to the path of the knife by engagement with its sewing-rib so that the trimmed margin will bear a predetermined relation to the previously formed sewing-rib. In this way the location of the trimming cut on the margin of the insole with relation to the sewing-rib will be definitely determined.

Welt insoles for standardized shoes such as above referred to are provided with a pair of jig-holes punched through their heel-seat portions. These jig-holes are adapted to receive a pair of pins which are provided on the last for locating the insole upon the last bottom preparatory to the performance of the lasting operation. In order that the insole may be properly located upon the last, it is necessary that the jig-holes be accurately located at predetermined points on the insole. It is not practicable to punch the holes through the insole at the time the several component layers of the insole are assembled, inasmuch as the layers are then in a heated state, and consequently are liable to shrink as they cool, with the result that the jig-holes will not be uniformly located in different insoles. Neither is it desirable to punch the jig-holes by an entirely separate operation after shrinkage has taken place on account of

the additional time and expense required therefor.

Another object of the invention is to provide, in a machine for trimming the margins of welt insoles, means for punching one or more jig-holes in the insole. In carrying out the feature of the invention it is proposed to punch these jig-holes during the work-engaging movement of the clamp by the pressure of a cutting-block, mounted upon the clamp, against a pair of dies or punches carried by the pattern.

The invention further consists in the features of construction and combination of parts hereinafter described and particularly pointed out in the appended claims, the advantages of which will be apparent to those skilled in the art.

The various features of the invention will be best understood from a description of the preferred embodiment thereof illustrated in the accompanying drawings, in which the invention has been shown as embodied in a machine which is similar, in its general characteristics, to the Planet sole rounding machine disclosed in Letters Patent of the United States, No. 882,009, granted March 17, 1908, upon application of Benjamin F. Mayo.

In the drawings, Figure 1 is a view, in front elevation, of the machine; Fig. 2 is a plan view, on an enlarged scale, showing particularly the pattern, the trimming knife and the mechanism for supporting and actuating the knife; Fig. 3 is a top plan view of the pattern, this view being on a still further enlarged scale; Fig. 4 is an inverted plan view of the clamp for holding the insole against the pattern; Fig. 5 is a view, in side elevation, of the pattern and the clamp, the latter being shown in its raised or inoperative position and the pattern having an insole resting thereon in position to be engaged by the clamp; Fig. 6 is a view similar to Fig. 5, showing an insole held against the pattern by the clamp in position for the trimming operation; Fig. 7 is a detailed sectional view taken on the line 7—7 of Fig. 6; Fig. 8 is a detailed perspective view of the trimming knife; Fig. 9 is a view, in front elevation and on an enlarged scale, of a portion of the machine illustrated in Fig. 1, showing particularly the manner in which the clamp is supported; Figs. 10, 11 and 12 are detailed sectional views taken on the lines 10—10, 11—11 and 12—12, respectively, of Fig. 9; and Fig. 13 is a detailed perspective view of one of the parts associated with the clamp.

As illustrated in Figs. 1 and 2 of the drawings, the pattern, which is indicated at 14, is held stationary by a pair of vertical posts 16, rising from a block 18 upon which the posts are mounted with provision for adjustment toward and from each other to enable them to support patterns of different

sizes. The block 18 is rigidly secured to the upper end of a cylindrical standard 20 which is bolted to the base 22 of the machine.

During the insole rounding or trimming operation, the insole is securely held against the pattern 14 by means of a clamp 24 carried by a clamp-carrier 26 pivotally secured to the lower end of a slide 28 that is mounted for vertical reciprocation in an overhanging portion 30 of the machine frame. The slide 28 is connected to the forward end of an actuating lever 32, the opposite end of which is engaged by a rod 34 which is connected with a foot treadle 36 in such a manner that the depression of the treadle will actuate the slide 28 to force the clamp 24 toward the pattern 14. The clamp is raised by means of a coiled spring 38 connected at one end to the lever 32 and at the opposite end to the frame of the machine.

The rounding or trimming knife, which is indicated at 40, is caused to travel around the pattern 14 by the rotation of a rotary support 42, the hub of which rests upon the hub of a stationary cam 44 that is fixed upon the standard 20. As best shown in Fig. 2, the knife 40 is secured to a holder 46 mounted at the end of an arm 48 rigidly secured to a segmental shaped plate 50 pivotally mounted at 52 upon a carrier 54. The carrier 54 is mounted to slide upon a guide 56 that is pivoted upon the rotary support 42. The guide 56 is rocked and the carrier 54 moved inward and outward on the guide, as the rotary support 42 is revolved to give the proper movements to the knife, by means of the stationary cam 44 and a second stationary cam 58 (Fig. 1) which are connected with the guide and with the carrier respectively.

The general arrangement of the above named parts and their mode of operation, so far as already described, is the same as that set forth in the hereinbefore mentioned Letters Patent No. 882,009. With the exception of the pattern, the clamp-carrier and the rounding knife, which are especially designed to accomplish certain of the objects of the present invention, the particular construction of all the parts above described is or may be substantially the same as that of corresponding parts of the machine of said Letters Patent. The rounding knife is yieldingly held against the pattern by mechanism substantially the same as that which has been heretofore employed in machines of this general character, the construction of this means being described in the last-mentioned Letters Patent.

The rotary support 42 is driven to cause the trimming knife to travel around the pattern, through a driving shaft 60 (Fig. 1) which is connected with said support by means of a bevel pinion 62 fast upon the end of the driving shaft and engaging a beveled gear 64 secured to the underside

of the support 42. Motion is imparted to the driving shaft 60 through speed changing mechanism indicated generally at 66 in Fig. 1. This mechanism 66 is substantially the same as corresponding mechanism disclosed in Letters Patent of the United States, No. 1,048,511, granted December 21, 1912, upon application of W. G. Eaton.

The pattern 14 and the clamp 24 of the machine shown in the drawings are constructed and arranged for use in connection with manufactured welt insoles in which the feather or sole margin is molded around the toe, as illustrated and described in the hereinbefore mentioned Letters Patent No. 1,578,359. A manufactured welt insole having its feather molded at the toe, as disclosed in said Letters Patent, is illustrated at 68 in Figs. 5 and 6.

As shown in Figs. 3, 5, 6 and 9, the pattern 14 consists of a sole-shaped plate which is constructed and arranged to support the insole during the trimming operation, while the edge of the plate guides the rounding knife and thus serves to determine the shape and size of the trimmed sole. In order that the dimensions of all insoles which are trimmed with the aid of the pattern 14 shall be the same with regard to the relation of the sewing-rib to the edge of the insole, the pattern 14 is so constructed that an insole placed thereon by the operator will be located with its margin projecting beyond the edge of the pattern the requisite amount to properly determine the desired relation of the sole edge to the sewing-rib. To this end, the upper face of the plate constituting the pattern is recessed or cut away, as indicated at 70, (see also Fig. 7) to receive the sewing-rib of the insole. The recess 70 is cut to a depth slightly greater than the height of the sewing-rib and extends across the upper face of the pattern plate from toe to heel and from one lateral margin to the other, leaving an endless flange 72 projecting upwardly from the margin of the pattern. The upper edge of the flange 72 provides a flat face 74, adapted to engage the feather of the insole to support the insole during the trimming operation. In order that the marginal flange 72 of the pattern shall engage and properly support the moulded portion of the feather about the toe of the insole, the corresponding portion of the flange is built up above the plane of the upper edge of the remaining portion thereof to provide a raised sole supporting face 76. A pair of holes 78 extend through the pattern frictionally to receive a pair of short pins 80 (Fig. 9) which project vertically from heads 82 at the upper ends of the pattern supporting posts 16.

The clamp 24, as best shown in Figs. 4, 5, 6 and 9, is mounted on the clamp-carrier 26, in parallel relation to the pattern 14,

and consists of a plate having the same marginal contour as the pattern. The lower side of the clamp plate 24 is adapted to engage the unribbed face of an insole which is supported upon the pattern and to press the insole against the upper edge faces 74 and 76 of the marginal flange 72 on the pattern. To accommodate the moulded portion of the sole margin or feather about the toe of the insole, the marginal portion about the toe of the clamp plate is cut away or rabbeted to form a sole engaging face 84 (Figs. 4 and 5) that is complementary to the face 76 on the pattern. As the clamp is moved by the depression of the foot treadle 36, to bring the clamp into work-engaging position, the lower side of the clamp engages the unribbed face of the insole throughout the entire surface of the latter and securely clamps the margin of the insole against the

The clamp-carrier 26, as best shown in Figs. 9 to 12, inclusive, comprises a substantially rectangular frame having elongated upper and lower walls 86 and short end walls 88. The front side of the clamp-carrier frame is open while the rear side thereof is partially closed by longitudinal webs 90. Rising vertically from the upper wall 86 of the clamp-carrier is a tongue 92 which is received in a transverse slot 94 at the lower end of the slide 28. The clamp-carrier 26 is pivoted to the slide 28 by means of a horizontal pin 96 which extends transversely through the tongue 92 and through the forked lower ends of the slide. To insure rigidity of construction of the clamp-carrier 26, the carrier is strengthened by a pair of ribs 97 which extend outwardly in opposite directions from the tongue 92 along the outer face of the upper wall 86. The carrier is further reinforced by means of the webs 90 and also by a transverse web 98 which connects the central portions of the upper and lower walls 86.

The clamp-carrier is normally maintained in a fixed position, relatively to the slide 28 upon which it is pivoted, by means comprising a pair of pins 100 (Figs. 9, 10 and 12) which are supported upright in guideways 102 in the tongue 92, with the flat upper ends of the pins engaging the top wall of the slot in the lower end of the slide 28. The guideways 102 are arranged in the tongue 92 upon opposite sides of the hole through which the pivot pin 96 extends, the guideways consisting of holes which are bored through the tongue perpendicular to the upper end face thereof. The pins 100 are sustained in the guideways 102 by means of screws 104 which are screwed into the clamp-carrier frame from the rear side thereof and are provided with cone-shaped inner ends that severally project into the lower portions of the guideways 102 to engage a cone-shaped surface

formed at the lower ends of the pins 100. The screws 104 may be loosened to release the pins 100 and leave the clamp-carrier free to turn upon its pivot pin 96 as the clamp 24 is angularly adjusted with respect to the slide.

5 The clamp 24 is supported above the pattern 14 by means of clamp supports 108 (Figs. 9, 11 and 12) comprising cylindrical blocks each having a short pin 110 projecting axially from one end face and a screw-threaded stud 112 projecting axially from the opposite end face thereof. The pins 110 are adapted to fit tightly within a pair of holes 114 in the clamp 24 to frictionally support the clamp. The clamp supports 108 are secured to the lower wall 106 of the clamp-carrier with provision for adjustment toward and from each other, and also for a certain amount of adjustment transversely of the clamp-carrier for purposes which will hereinafter be explained.

10 To this end the studs 112 extend through longitudinal slots 116 (Fig. 10) in the lower walls 86 of the clamp-carrier, these slots being wider than the diameter of the studs to permit adjustment of the clamp supports transversely as well as longitudinally of the clamp-carrier.

15 The clamp supports 108 are secured to the clamp-carrier by means of nuts 118 which are provided on the free ends of the studs 112, a washer 120, large enough to overlap the side walls of the respective slot 116, being interposed between each nut 118 and the adjacent face of the lower wall 86 of the clamp-carrier.

20 The adjustment and clamping of the clamp supports 108 is further facilitated by means of a pair of washers 122 which are severally interposed between the upper end faces of the clamp supports 108 and the adjacent face of the lower clamp-carrier wall 86. The upper face of each washer 122, as best shown in Fig. 13, is provided with a pair of tongues or ribs 124, which are diametrically arranged on opposite sides of the central opening in the washer and which are adapted to fit within the longitudinal slots 116 in the clamp-carrier. The upper face of each clamp support 108 is provided with a pair of tongues or ribs 126 which radiate from diametrically opposite points on the stud 112. These tongues 126 fit into grooves 128 which are formed in the lower face of the washer 122 and diametrically disposed on opposite sides of the opening in the washer, these grooves extending in a direction perpendicular to the length of the ribs 124. The central openings in the washers 122 are elongated in a direction perpendicular to the length of the ribs 124, as indicated at 130 in Fig. 13, to permit relative movement between the washers and the clamp supports in said direction. With this construction, the washer 122 is free to move in the longitudinal slots 108 but is prevented by the tongues 124 from moving transversely

25 with relation to the clamp-carrier. The elongated

gated hole in the washer 122 and the tongue-and-slot connection between the clamp supports and the washers 122, however, permit the clamp supports to be shifted relatively to said washer in a transverse direction with respect to the clamp-carrier.

70 It is desirable that the edges of the pattern 14 and the edges of the clamp 24 shall be in exact alinement when the clamp is in work-engaging position so that the clamp will properly engage the margin of the insole, particularly where said margin is moulded around the toe, and also to prevent possibility of interference by the edge of the clamp with the proper guidance of the rounding knife by the pattern. It is also desirable that the sole margin shall be pressed against the pattern uniformly throughout the length of the former to insure that the insole will not slip under the pressure of the rounding knife. Accordingly, it is desirable to make certain setting-up adjustments of the clamp whenever the pattern and clamp are replaced by others of a different size or style. This preliminary adjustment of the clamp is effected in the following manner: The pattern is first placed in operative position upon the pins 80 carried by the pattern supporting posts 16. A clamp of a size corresponding to that of the pattern is placed on top of the pattern and manipulated by the operator until the edge of the clamp is brought into exact alinement with the edge of the pattern. The screws 104 and the nuts 118 having first been loosened to leave the clamp-carrier free to tilt slightly with respect to the slide 28 and to permit the clamp supports 108 to be readily shifted in the slots 116, the clamp-carrier is then moved downwardly by depression of the foot treadle until the pins 110 upon the clamp supports 108 are brought into engagement with the upper face of the clamp. Inasmuch as the holes 114 in clamps of different sizes are located at different distances from each other, it is necessary to adjust the clamp supports 108 toward or from each other in the slots 116 to bring the pins 110 into position for engagement with the holes in the clamp. If the pins cannot be brought into exact registry with the holes in the clamp plate by this adjustment, the clamp supports 108 may be shifted transversely with respect to the slots 116 sufficiently to permit the pins to register with the holes. After the pins have been brought into registry with the holes in the clamp plate, the foot treadle is further depressed to cause the pins to be projected into the holes and to press the clamp firmly against the pattern. Under the influence of this pressure, the clamp will readily and accurately adjust itself to bring its sole-engaging faces into the planes of the corresponding sole-engaging faces of the pattern. While the pressure is still maintained upon the clamp, the screws 104 are tightened to press

80 85 90 95 100 105 110 115 120 125 130

the pins 100 against the slide 28 and thus rigidly secure the clamp-carrier to the slide in its adjusted position relatively to the latter. The nuts 118 are also tightened to secure the clamp supports 108 in their adjusted positions in the slots 116 of the clamp-carrier. The clamp, which is then permitted to return to its normal elevated position, has been so adjusted relatively to the pattern, that it will thereafter cooperate with the latter properly to clamp the insole which fits the pattern for the trimming operation.

While the clamp is descending into work-engaging position, the required jig-holes are punched through the heel-seat of the insole. In the construction shown, the jig-holes are produced by means of a pair of dies or punches 134 (Figs. 3, 5 to 7 and 9) which are mounted on the pattern and are arranged to cooperate with a cutting-block 136 (Figs. 4 to 7) on the clamp, as the clamp moves toward the pattern. It is to be understood, however, that the present invention is not limited to punches which are mounted upon the pattern or to a cutting-block carried by the clamp. The punches 134 are located on the center line of the heel portion of the pattern at the required distance from the rear extremity thereof. The lower ends of the punches are set into holes 138 which extend through the pattern. Each punch is provided with an external annular flange 140, which is seated against the recessed upper face of the pattern to support the punch against the pressure of the cutting-block. The cutting edges of the punches are located above the plane of the upper edge faces 74 of the flange 72 on the pattern, a distance equal to the thickness of the insoles which are to be operated upon so that the punches will not interfere with the clamping action of the clamp 24 but will be adapted to cut completely through the insole material when the insole has been clamped against the pattern.

The cutting-block 136 is set into the clamp 24 with its lower face flush with the lower face of the clamp. The cutting-block is preferably constructed of soft metal which will withstand repeated cooperation with the punches without injuring the cutting edges of the latter. The hole 114 at the heel end of the clamp 34, which receives the pin 110 of the respective clamp support 108, extends through the cutting-block to permit said pin to project its entire length into the clamp.

When an insole has been positioned upon the pattern 14 with its sewing-rib received in the recess 70, the heel-seat portion of the ribbed face of the insole will lie in contact with one or both of the punches, as indicated in Fig. 5. When the clamp is brought down, the heel-seat portion of the insole is forced down over the punches and the jig-holes are thus produced. The scrap cut by the punches

punches, as successive insoles are operated upon, and this scrap is finally discharged from the punches and falls beneath the pattern. By means of the strengthening ribs 90, 98, a clamp-carrier of extremely rigid construction is provided, thus insuring against possible upward yielding movement of the heel end of the clamp as the cutting-block 136 presses the insole against the punches 134.

After the insole has been clamped against the pattern and the jig-holes have been punched through the heel seat of the insole, the rounding knife 40 is actuated to trim the sole margin which projects beyond the edge of the pattern. It has been found in operating upon laminated insoles that the margins thereof are not always stiff enough to permit a rounding knife of the usual construction to cut in from the edge of the insole to a point where the knife engages the edge of the pattern, as is the custom in rounding leather soles. To avoid the necessity of cutting in from the edge of the insole at the start of the trimming operation, the rounding knife 40, with which the illustrated machine is provided, has embodied therein a certain novel feature of construction which enables the knife to penetrate the sole margin from one face instead of from the edge thereof.

The rounding knife is illustrated in detail in Fig. 8. As therein shown the knife comprises a blade having a vertical cutting edge 142. The blade of the knife is thicker at its lower end to provide a base 144 which is adapted to be clamped in the usual manner to the knife holder 46, as illustrated in Fig. 2. The upper end of the knife 40 is beveled, as shown clearly in Fig. 8, to produce a sharp point 146 for piercing the insole material as the insole is forced down over said point.

In accordance with the usual practice, the trimming knife is retracted from the pattern to permit another untrimmed sole to be placed upon the pattern with its margin overlapping the edge. In the operation of the present machine, the trimming knife is normally held against the edge of the pattern not only throughout the trimming operation but it is permitted to remain in contact with the pattern after the sole has been trimmed. When the clamp 24 is brought down upon the sole through pressure on the treadle 36 the portion of the margin of the insole which projects above the point of the rounding knife will be forced down over the knife until the knife cuts completely through the margin. The knife is then in position for commencing the trimming cut as soon as the insole is clamped without the necessity of cutting in from the edge of the insole. At the completion of the trimming operation it is not necessary for the operator manually to retract the rounding knife from the pattern and consequently a saving of time is effected. While it is preferred to employ the specific construction

and arrangement of parts herein shown and described, it will be understood that this construction and arrangement is not essential except so far as specified in the claims and 5 may be changed or modified without departing from the spirit and true scope of the invention.

What is claimed as new is:—

1. A machine for operating upon marginally ribbed soles having, in combination, a rounding knife for trimming the margin of a sole, means for guiding the rounding knife during the trimming operation, and means for supporting the sole and cooperating with 10 the rib thereon to hold the sole in predetermined relation to the supporting means for the trimming operation.
2. In a machine for operating upon soles having a marginal rib, in combination, a 15 rounding knife for trimming the margin of a sole, and a pattern for guiding the knife having a marginal face for supporting the sole adjacent to the rib during the trimming operation whereby the sole is contoured in 20 definite relation to the rib.
3. A sole rounding machine having a pattern and a co-operating clamp member, one of said parts being provided with means for engaging a sewing rib of an insole to locate 25 the insole relatively to the pattern.
4. A sole rounding machine having a pattern and a co-operating clamp member, the pattern being provided with means arranged to cooperate with the sewing rib of an insole 30 to position the insole relatively to the pattern.
5. A machine for operating upon ribbed insoles having, in combination, a rounding knife for trimming the margin of the sole, a pattern constructed and arranged to support the insole by engagement with its feather and to guide the rounding knife, means for locating the insole in a predetermined 35 position upon the pattern, and means for clamping the feather of the insole against the pattern.
6. A machine for operating upon welt insoles having, in combination, a pattern adapted to support an insole and provided with a recess for receiving the sewing-rib, the recess having a wall constructed and arranged to 40 locate the insole relatively to the pattern, and a rounding knife guided by the pattern for trimming the margin of the insole.
7. In a machine for operating upon welt insoles, the combination with a rounding knife for trimming the margin of the insole of a pattern having an edge for guiding the knife, and an upstanding flange for supporting the insole by engagement with the feather and for cooperating with the sewing-rib definitely to locate the insole relatively to the pattern.
8. In a machine for operating upon a welt insole having a portion of the feather offset 45 from the plane of the insole, the combination

with a rounding knife for trimming the margin of the insole of a pattern having an edge for guiding the knife, and a marginal flange on the pattern shaped to engage the offset portion of the feather and the outer face of the sewing-rib to support the insole and locate it relatively to the pattern. 70

9. In a machine for operating upon a welt insole having a portion of the feather offset from the plane of the insole, the combination with a rounding knife for trimming the margin of the insole of a pattern having an edge for guiding the knife and having a marginal flange projecting from the side of the pattern and shaped to engage one face of the offset portion of the feather, and a clamp for engaging the other face of said offset portion for holding the insole against the pattern. 75

10. A machine for operating upon insoles having, in combination, a pattern and a knife mounted for relative movement and constructed and arranged to support an insole and trim its margin, and means for holding the insole against the pattern and for punching a jig-hole through the insole. 80

11. A machine for operating upon insoles having, in combination, a pattern adapted to support an insole, a clamp plate for holding the insole against the pattern, a rounding knife guided by the pattern for trimming the margin of the insole, and a punch arranged to cooperate with the clamp plate to punch a jig-hole in the insole. 85

12. A machine for operating upon insoles having, in combination, a pattern adapted to support an insole, a clamp plate for holding the insole against the pattern, a rounding knife guided by the pattern for trimming the margin of the insole, a die, and a cutting-block for cooperating with the die to punch a jig-hole in the insole. 90

13. A machine for operating upon insoles having, in combination, a pattern adapted to support an insole, a clamp plate for holding the insole against the pattern, a rounding knife guided by the pattern for trimming the margin of the insole, a cutting-block carried by the clamp plate, and a die on the pattern arranged to cooperate with the clamp plate to punch a jig-hole in the insole. 95

14. A machine for operating upon insoles having, in combination, a pattern adapted to support an insole, a die for cutting a jig-hole in the insole, means on the pattern for locating the insole in a predetermined position thereon, a clamp for holding the insole against the pattern, a cutting-block for cooperating with the die, and a rounding knife guided by the pattern for trimming the margin of the insole. 100

15. A machine for operating upon insoles having, in combination, a pattern adapted to support an insole, a die for cutting a jig-hole in the insole, means for holding the insole against the pattern and cooperating with 105

the die to cut the jig-hole in the insole, and a rounding knife guided by the pattern for trimming the margin of the insole.

16. A machine for operating upon welt insoles having, in combination, a sole-shaped pattern adapted to support an insole, a clamp for holding the insole against the pattern, a pair of dies on the pattern for punching jig-holes in the heel portion of the insole, a cutting block on the clamp for cooperating with the dies to punch the holes, means on the pattern for engaging the sewing-rib to locate the insole thereon, and a rounding knife guided by the pattern for trimming the margin of the insole.

17. A machine for operating upon insoles having, in combination, a pattern constructed and arranged to support the insole and locate it in a predetermined position thereon, a clamp plate for holding the insole against the pattern, a knife for rounding the pattern to trim the margin of the insole, and a die on the pattern for cooperating with the clamping plate to punch a jig-hole in the insole after the latter has been located upon the pattern.

18. In an insole trimming machine of the type in which a pattern and a knife are mounted for relative movement to trim the margin of the insole, a pointed end on the knife for piercing said margin at a point located inwardly from the edge thereof, and means for relatively moving the insole and the knife in the direction of the length of the knife to force the insole over the point of the knife.

19. In an insole trimming machine the combination with a pattern upon which an insole is positioned with its margin projecting beyond the edge of the pattern and a clamp plate for holding the insole against the pattern, of a rounding knife guided by the pattern for trimming the projecting margin of the insole, said knife being normally maintained in contact with the pattern and being disposed at right angles to the insole supporting face of the pattern and constructed and arranged to be forced in the direction of its length through the margin of the insole as the latter is pressed against the pattern by the clamp plate.

20. A machine for operating upon soles having, in combination, a pattern adapted to support a sole, a rounding knife guided by the pattern for trimming the margin of the sole, a clamp member for holding the sole against the pattern, a carrier for the clamp member, a slide upon which the carrier is pivotally mounted, and means for securing the carrier to the slide in various positions of angular adjustment with respect to the slide.

21. A machine for operating upon soles having, in combination, a pattern adapted to support a sole, a rounding knife guided by

the pattern for trimming the margin of the sole, a clamp plate for holding the sole against the pattern, a carrier for the clamp plate, a slide upon which the carrier is pivotally mounted, a pair of pins severally mounted in guideways in the carrier on opposite sides of its pivotal connection with the slide, the pins being severally arranged with one end engaging a fixed part of the slide, and means for engaging the opposite ends of the pins adapted to be adjusted to secure the pins in different positions in the guideways positively to secure the carrier to the slide in different positions of angular adjustment with respect to the slide.

22. A machine for operating upon soles having, in combination, a pattern adapted to support a sole, a rounding knife guided by the pattern for trimming the margin of the sole, a clamp plate for holding the sole against the pattern during the trimming operation, a carrier upon which the clamp plate is mounted so as to permit adjustment thereof both longitudinally and transversely relatively to the carrier, a slide for supporting the carrier, and means for securing the carrier to the slide in various positions of angular adjustment with respect thereto.

23. A machine for operating upon soles having, in combination, a pattern adapted to support a sole, a rounding knife guided by the pattern for trimming the margin of the sole, a clamp for holding the sole against the pattern, supporting means to which the clamp is adapted to be secured, a carrier upon which said supporting means is mounted so as to permit adjustment thereof both longitudinally and transversely with respect to the carrier, a slide for supporting said carrier, and means for securing the carrier to the slide in various positions of angular adjustment with respect thereto.

24. A machine for operating upon soles having, in combination, a sole-shaped pattern adapted to support a sole, a rounding knife guided by the pattern for trimming the margin of the sole, a sole-shaped clamp plate for holding the sole against the pattern, a pair of supports to which the clamp plate is secured, a carrier upon which said supports are mounted, the carrier being slotted to receive the supports and to permit adjustment thereof toward and from each other and the slots being constructed and arranged to permit adjustment of the supports in directions perpendicular to the direction of the first-mentioned adjustment, and means for clamping the supports in adjusted position upon the carrier.
